UNITED STATES PATENT OFFICE.

PATRICK J. HEALEY, OF JERSEY CITY, NEW JERSEY.

SEWER-CLEANING DEVICE.

1,313,378.

Specification of Letters Patent.

Patented Aug. 19, 1919.

Application filed February 1, 1919. Serial No. 274,427.

To all whom it may concern:

Be it known that I, PATRICK J. HEALEY, a citizen of the United States, and a resident of Jersey City, in the county of Hudson and 5 State of New Jersey, have made and invented certain new and useful Improvements in Sewer-Cleaning Devices, of which the following is a specification.

My invention relates to sewer cleaning devices designed to remove such accumulation of solid material as may have collected within a sewer, or rather in a section thereof between two manholes, the invention having particular reference to that type or class of 10 sewer cleaning devices in which a bucket is drawn through the sewer by means of a suitable rope and during which it scoops up a load of the material to be removed, after which the same is elevated to the surface of 15 the ground through a suitable manhole; an example of which class of devices is shown in my Patent No. 775,677, for machine for cleaning sewers, patented November 22, 1904, and of which device the sewer cleaning 20 mechanism to which this present application relates is an improvement.

The object of the invention disclosed and claimed herein is to provide a sewer cleaning mechanism or device of the class above 25 referred to which may be operated entirely from one end of the sewer or section thereof to be cleaned.

A further object of my invention is to provide improved means for accomplishing the dumping of the contents of the bucket employed after it has been elevated to the surface of the ground; and further objects of my invention will appear in the following 35 description, wherein the particular features thereof are pointed out at length.

With the above and other objects in view, my invention consists in the improved sewer cleaning device illustrated in the accompanying drawings, described in the following 45 specification, and particularly claimed, and in such variations and modifications thereof as will be obvious to those skilled in the art to which my invention relates.

In the drawings accompanying and forming a part of this specification, and wherein the preferred embodiment of my invention is illustrated:

Figure 1 is a view showing my improved sewer cleaning device installed in a section 55 of sewer to be cleaned; and

Fig. 2 is a view upon a larger scale illustrating my invention and in which certain portions thereof are shown in two positions, in order that the operation thereof may be better explained.

Referring now to the drawings, the reference numeral 5 designates a section of sewer to be cleaned, and 6 and 7 are two manholes leading from the surface of the ground into the sewer and through which entrance may be had thereto, these being the usual manholes present in sewer systems in common use.

Located adjacent the manhole 6 is winding mechanism of any suitable form, so far as 60 my invention regarded in its broader aspects is concerned, which mechanism, however, is shown as in the form of two winding drums 8, 9, both of which are operated from an internal combustion or other engine 10, to 65 thereby operate the mechanism. The winding drums are commonly operated from the engine through a drive chain and suitable gearing, suitable clutch and brake mechanism being ordinarily provided for connecting 70 and disconnecting each drum with the engine, so that either drum may be operated independently of the other.

The reference numeral 11 designates the bucket of my improved sewer cleaning device 75 which is drawn back and forth through the section of the sewer to be cleaned, the same being provided with wheels 12 in order to reduce the friction, as will be appreciated. The main body portion of the bucket may be 80 of various forms, the form illustrated in the drawings being cylindrical in cross section. The lower end of the body of the bucket is closed by two doors 13 pivotally connected to the lower end of the side wall thereof, 85 and with which doors the ends of two flexible members such as chains 14 are connected, as best shown in Fig. 2. These flexible members extend through guides 15 secured to the inner surface of the wall of the bucket 90 and are connected at their upper end with a ring 16; with which ring the end of a lifting rope is connected to thereby move the bucket to the left, Fig. 1, and then lift it through the manhole 6 and dump its contents into a 95 tank, wagon, or other receptacle, as indicated in Fig. 2.

The bucket 11 is filled by moving the same to the right, Fig. 1, while the lower of the swinging doors 13 is open, so that as 100

the bucket is moved the end of the door which slides along the bottom of the sewer will scoop up material to be removed and cause the entrance thereof into the body of the bucket.

The engine 10 and winding or hoisting mechanism is commonly supported upon any suitable base such as is indicated by the reference numeral 17, and 18 designates a boom 10 or crane the lower end of which is pivotally connected with the base 17 at 19, so that the boom may be swung in a vertical plane and into the two extreme positions in which it is illustrated in Figs. 1 and 2 in full and 15 dotted lines. The upper or free end of this boom supports a pulley or sheave block 20 having two wheels or sheaves to accommodate two ropes in the embodiment of my invention illustrated; and the position of 20 said boom is controlled by a rope 21, one end of which is connected at 22 with a cross bar 23 of a vertically arranged framework 24 carried by the base 17, and which rope passes about a pulley 25 carried by the 25 boom, and thence over the cross bar 23 and to the left hand end of the framework, where it is secured to any suitable fastening device such as is indicated by the reference numeral 26. The purpose of this rope is to 30 permit the boom to swing into the position shown in full lines in Fig. 2 when the bucket is to be dumped, and to return the same into the position shown in dotted lines in Fig. 2, and in Fig. 1, when the bucket is to be lowered into or drawn up through the manhole 6. It will be appreciated that this swinging movement of the boom may be accomplished by any rope or equivalent member 35 whereby the boom may be operated to attain the result above referred to.

The reference numeral 27 designates a fixed abutment secured in place at the end of the section of sewer to be cleaned which is remote from the winding mechanism and 45 other elements of the device, and which abutment serves as a fixed support for a pulley 28; and a second fixed abutment 29 is secured in place within the sewer at the end thereof adjacent the hoisting drums, and 50 which last mentioned abutment serves as a support for two pulleys 30, 31.

The reference numeral 32 designates a guide pulley rope which extends from the surface of the ground where its end is secured to any support downward through the manhole 6 and about the pulley 31, and the free end of which rope is connected with a guide pulley 33; the purpose of said guide pulley being to change the direction of the 55 rope whereby the bucket 11 is moved to the left from the horizontal to the vertical, and to permit the bucket to be lifted through the manhole, during which movement the guide pulley moves upward along with the 60 bucket; the end of the rope which is secured

to a fixed support at the surface of the ground being unfastened at the beginning of the upward movement of the bucket and as the same is tipped from the horizontal position in which it is shown in Fig. 1 into a 70 vertical position preparatory to hoisting it through the manhole 6, as will be appreciated.

The movement of the bucket to the right is produced by a rope 34 operated by the 75 winding drum 8 and which rope passes upward and about one of the sheaves of the pulley 20, thence downward through the manhole 6 and about the pulley 30, thence to the remote end of the section of sewer to 80 be cleaned and about the pulley 28, and thence to the bucket; the end of said rope being connected either directly with the body of the bucket or with the lower of the swinging doors thereof, the latter being the 85 method of connection illustrated in the drawings. It will be understood from the above that upon rotary motion being imparted to the said drum 8 the bucket will be moved to the right, during which the 90 solid matter will be scooped up and carried into the body of the bucket, thus filling the same.

After the bucket 11 has been filled by a movement to the right it is drawn to the 95 left by means of a lifting rope 35 operated by the winding drum 9 and which rope passes upward and about the other of the sheaves of the pulley 20, thence downward through the manhole 6 and through the 100 guide pulley 33, thence along the section of sewer to be cleaned to the bucket; where it is connected with the ring 16 at the ends of the flexible members 14, the other ends of which flexible member are connected with 105 the doors 13 as hereinbefore explained. The first movement of the said rope to the left will obviously close the doors 13, thus retaining whatever material may have been scooped up by the bucket, and the load which 110 the bucket contains is obviously supported by the said flexible members operating through the doors while the bucket is being moved along and lifted through the manhole 6, and until the same is discharged from the 115 bucket in the manner hereinafter explained.

When the bucket reaches about the position indicated by dotted lines in Fig. 1, the free end of the guide pulley rope 32 at the 120 surface of the ground is released, whereupon and as the bucket is lifted through the manhole 6 the guide pulley passes along with the bucket, as indicated in Fig. 2. It will of course be understood that the guide pulley rope is drawn in as the bucket descends 125 through the manhole 6, in order that the said pulley may be in proper position for a subsequent operation, it being appreciated that several trips of the bucket through the section of sewer to be cleaned are ordinarily 130

necessary in order to remove all the sediment or solid material therefrom.

The dumping of the contents of the bucket 11 after it has been moved into the position shown in Fig. 2, is accomplished by a dumping rope 36 having a hook 37 at its free end, and which rope extends through or about guiding means located adjacent the end of the boom, as through a loop or eye 10 38 carried by the pulley block 20, and the other end of which is adapted to be secured to a fixed support indicated by the reference numeral 39, and which dumping rope serves to support the body of the bucket and permit the lifting rope to be slackened; whereupon the doors will open and the contents thereof escape through the bottom of the bucket.

In order to accomplish this operation two 20 chains 40 are provided, the lower ends of which are secured to the body of the bucket in any way, as by eyes carried by the guides 15 hereinbefore referred to. The upper ends of these chains are preferably connected with 25 a ring 41 with which a hook 42 is connected through a short piece of chain, in order to provide for the convenient attachment or engagement of the hook 37 of the dumping rope with the bucket in such a manner that 30 the same may be supported by the dumping rope after it has been elevated and swung into the dumping position shown in Fig. 2, whereupon and as the lifting rope 35 is slackened the doors 13 will open and permit the contents of the bucket to escape. 35 The hook 42 should be hooked into the ring 16 when the bucket is to be lowered through the manhole 6, in which condition it remains during the filling operation thereof, 40 and during the subsequent movement of the bucket to the left and while it is being lifted through said manhole, in order that the said hook may be in an easily accessible position when the hook 37 of the dumping rope 45 is to be engaged therewith.

It will be appreciated that the dumping rope is connected with the bucket when the same reaches about the position in which it is shown in dotted lines in Fig. 2 upon its 50 upward journey, and that said dumping rope is disconnected from the bucket before the same passes back into the sewer. The said rope is of course kept taut while the bucket is passing from the dotted line position shown in Fig. 2 into the dumping position, and is then fastened to the securing member 39, or held in the hand, while the bucket is dumped. Thereafter and until the bucket reaches the dotted line position in 55 Fig. 2 upon its return movement into the sewer the said rope is slackened, and permitted to move through the guide 38, and the said rope is unhooked from the bucket when the same reaches the dotted line position referred to.

Having thus described and explained my invention, I claim and desire to secure by Letters Patent:

1. In a sewer cleaning device of the class described and in combination with two winding drums located adjacent each other, and means for operating each of said drums independently of the other; a bucket; a boom the lower end of which is pivotally connected with a suitable support so that it may swing in a vertical plane; a pulley supported at the free end of said boom; a fixed abutment secured in place within a section of sewer to be cleaned, and at the end thereof adjacent said drums; a pulley supported by said abutment; a second fixed abutment secured in place within the section of sewer to be cleaned, and at the end thereof remote from said drums; guiding means located within the section of sewer to be cleaned, and at the end thereof adjacent said drums; a rope operated by one of said drums and passing about the pulley carried by said first-mentioned abutment, thence along a section of sewer to be cleaned, 90 thence about the pulley carried by said second-mentioned abutment, and the end of which rope is connected with said bucket to thereby move the same in one direction; a lifting rope operated by the other of said drums and passing into operative relation with said guiding means whereby its direction is changed, and the end of which is connected with said bucket to thereby move the same in the other direction, and to lift it 100 from the sewer; and means for discharging the contents of said bucket after it has been lifted from the sewer.

2. In a sewer cleaning device of the class described and in combination with two winding drums located adjacent each other, and means for operating each of said drums independently of the other; a bucket; a boom the lower end of which is pivotally connected with a suitable support so that it may swing in a vertical plane; a pulley supported at the free end of said boom; a fixed abutment secured in place within a section of sewer to be cleaned, and at the end thereof adjacent said drums; two pulleys supported by said abutment; a second fixed abutment secured in place within a section of sewer to be cleaned, and at the end thereof remote from said drums; a rope operated by one of said drums and passing about one of the pulleys carried by said first-mentioned abutment, thence along a section of sewer to be cleaned, thence about a pulley carried by said second-mentioned abutment, and the end of which rope is connected with said bucket to thereby move the same in one direction; a guide pulley rope extending about the second of the pulleys carried by said first-mentioned abutment, and the end of which is connected with a guide pulley; a 130

lifting rope operated by the other of said drums and passing about the pulley carried by said boom, and through said guide pulley, and the end of which is connected with 5 said bucket to thereby move the same in the other direction and to lift it from the sewer; and means for discharging the contents of said bucket after it has been lifted from the sewer.

10 3. In a sewer cleaning device of the class described and in combination with two winding drums located adjacent each other, and means for operating each of said drums independently of the other; a bucket; a 15 boom the lower end of which is pivotally connected with a suitable support so that it may swing in a vertical plane; a rope operatively connected with said boom and whereby its position may be controlled; a pulley 20 supported at the free end of said boom and having two sheaves; a fixed abutment secured in place within a section of sewer to be cleaned, and at the end thereof adjacent said drums; two pulleys supported by said 25 abutment; a second fixed abutment secured in place within the section of sewer to be cleaned, and at the end thereof remote from said drums; a rope operated by one of said drums and passing about one of the sheaves 30 of the pulley carried by said boom, thence about one of the pulleys carried by said first-mentioned abutment, thence along the section of sewer to be cleaned, thence about the pulley carried by said second-mentioned 35 abutment, and the end of which rope is connected with said bucket to thereby move the same in one direction; a guide pulley rope extending about the second of the pulleys carried by said first-mentioned abutment, and the end of which is connected 40 with a guide pulley; a lifting rope operated by the other of said drums and passing about the other of the sheaves of the pulley carried by said boom, and through said guide 45 pulley, and the end of which is connected with said bucket to thereby move the same in the other direction, and to lift it from the sewer; and means for discharging the contents of said bucket after it has been 50 lifted from the sewer.

4. In a sewer cleaning device of the class described; a bucket comprising a body portion or shell; two doors pivotally connected with said shell and adapted to close the lower end thereof; two oppositely located guides carried by said shell; lifting means comprising two flexible members connected together at their upper ends and extending one through each of said guides, and the 55 lower ends of which are connected one with each of said doors; a lifting rope connected with said flexible members; means for lifting said bucket and for moving the same into a position to be dumped; and means 60 independent of said lifting rope and flexible

members for supporting said bucket when the contents thereof are to be dumped, so that said doors will open when said lifting rope is slackened.

5. In a sewer cleaning device of the class 70 described, a swinging boom; a pulley carried by the free end of said boom; a lifting rope extending through said pulley; a bucket comprising a body portion or shell; two doors pivotally connected with said shell and adapted to close the lower end thereof; two oppositely located guides carried by said shell; lifting means comprising two flexible members located within said bucket and connected together at their upper ends, and extending one through each of said guides, and the lower ends of which are connected one with each of said doors, and with which lifting means the end of said lifting rope is connected; means independent of said flexible members and connected with said bucket for supporting the same when the contents thereof are to be dumped; and a dumping rope extending about guiding means located adjacent the free end of 80 said boom and the end of which may be connected with said bucket supporting means, to thereby support said bucket and permit said doors to open when said lifting rope is slackened.

5. In a sewer cleaning device of the class 85 described, a boom, a pulley carried by the free end of said boom, a lifting rope extending through said pulley, a bucket comprising a body portion or shell, two doors pivotally connected with said shell and adapted to close the lower end thereof, lifting means comprising two flexible members located within said bucket and connected together at their upper ends, and the lower ends of 90 which are connected one with each of said doors, and with which lifting means the end of said lifting rope is connected; means independent of said flexible members and connected with said bucket for supporting the same when the contents thereof are to be dumped; and a dumping rope extending about guiding means located adjacent the free end of said boom and adapted to support said bucket while it is being dumped.

7. In a sewer cleaning device of the class 100 described, suitable winding mechanism; a bucket; a boom; a pulley supported at the free ends of said boom; a fixed abutment secured in place within a section of sewer to be cleaned, and at the end thereof adjacent said winding mechanism; a pulley supported by the said abutment; a second fixed abutment secured in place within the section of sewer to be cleaned, and at the end 105 thereof removed from said winding mechanism; guiding means located within the section of sewer to be cleaned, and at the end thereof adjacent said winding mechanism; a rope operated by said winding mechanism 110

and passing about the pulley carried by said first-mentioned abutment, thence along a section of sewer to be cleaned, thence about the pulley carried by said second-mentioned abutment, and the end of which rope is connected with said bucket; and a lifting rope operated by said winding mechanism and passing about guiding means located at the end of the section of sewer to be cleaned 10 which is adjacent said winding mechanism, whereby its direction is changed, and the end of which rope is connected with said bucket.

8. In a sewer cleaning device of the class 15 described, winding mechanism; a bucket; a boom; a pulley supported at the free end of said boom; a fixed abutment secured in place within the section of sewer to be cleaned, and at the end thereof adjacent said winding mechanism; two pulleys supported by 20 said abutment; a second fixed abutment secured in place within the section of sewer to be cleaned, and at the end thereof remote from said winding mechanism; a rope op-

erated by said winding mechanism and passing about one of the pulleys carried by said first-mentioned abutment, thence along the section of sewer to be cleaned, thence about a pulley carried by said second-mentioned abutment, and the end of which rope is connected with said bucket; a guide pulley rope extending about the second of the pulleys carried by said first-mentioned abutment, and the end of which is connected with a guide pulley; and a lifting rope operated 30 by said winding mechanism and passing about the pulley carried by said boom and through said guide pulley, and the end of which is connected with said bucket.

Signed at New York, borough of Manhattan, in the county of New York, and State of New York, this 30th day of January, A. D. 1919.
